UNITED STATES PATENT OFFICE.

EMERY M. WOOD, OF CHICAGO, ILLINOIS.

FOLDING BED.

SPECIFICATION forming part of Letters Patent No. 410,565, dated September 3, 1889.

Application filed March 2, 1889. Serial No. 301,798. (No model.)

To all whom it may concern:

Be it known that I, EMERY M. WOOD, a citizen of the United States, residing at Chicago, in the county of Cook and State of Illinois, have invented a new and useful Folding Bed, of which the following is a specification.

My invention relates to a bed standing at full length upon its head and with its bottom 10 in front when not in use, and brought to a horizontal position for use by swinging the top or foot end forward and downward; and the objects of my invention are to support the bed in the upper half of this swing by an 15 expanding floor-base formed at the back by the head of the bed-case itself resting upon the floor, and at the front by the foot-rollers of a two-legged stool pivoted at its top to the bottom of the bed-case and connected by 20 springs and folding braces to the head of the case, the feet of the stool rolling forward against the resistance of the springs until arrested by the braces and then becoming a rigid head-support whereon the bed is sufficiently poised to be easily swung to or from 25 its horizontal position; also, to provide mechanism causing the bedding to be sunk wholly within the bed-case by the closing of the pivoted head and foot boards of the bed. I attain 30 these objects by the mechanism illustrated in the accompanying drawings, in which—

Figure 1 is a central vertical section lengthwise of the horizontal bed. Fig. 2 shows two 35 half-end elevations of the same. Fig. 3 is a side elevation of the bed in its upright position, and showing in open lines two swinging positions marked, respectively, *x* and *y*. Fig. 4 is a combined half-front and half-rear elevation of the upright bed. Figs. 5, 6, 7, and 40 8 are separate, entire, and enlarged perspective views of the working parts, the more clearly showing their individual formation. The soft mattress and bedclothing, not being 45 material, are not shown in the drawings. Similar letters refer to similar parts throughout the several views.

The bed-case *C* is a rigid wooden shell, of which the bottom is paneled to form the 50 front of the upright bed. At the foot the bed has the ordinary hinged foot-leg support *L*, upon the cross-bar *t* of which is fixed the

handle *o*, to be grasped in swinging the bed up or down and in wheeling it about upon the floor when swung down. The two-legged 55 tilting stool *T*, Fig. 5, consisting of a pair of legs *T* and a cross-bar *t*, framed rigidly together, fits loosely between the side boards of case *C*, and at opposite points *e*, Fig. 1, and at the bottom of the case the stool is pivoted 60 to each of said side boards. The stool is provided with large floor-rollers *R*, with axles fixed in line with each other and parallel to the axial pivots *e*. The stool is also connected with the head of case *C* by a pair of closing-springs 65 *S*, Figs. 1 and 2, for the purpose of imparting elastic resistance to the stool as a front-leg support in all positions of the case, (shown in Fig. 3,) and also by a pair of jointed braces, *D*, Figs. 1 and 2, for the purpose of holding 70 the stool as a sole and rigid head-leg support in all positions, (not shown in Fig. 3,) or rather below position *y*. Lastly, a cast-iron weight of twenty pounds *w*, Figs. 1, 2, and 3, attached to the extreme head of the bed-case *C*, completes the mechanism for swinging the bed up or down and for wheeling it about in a room by handle *o*. Springs *S* are preferably coiled springs applied so as to receive and resist torsion, having the ends extending straight 75 as actuating-arms attached at their extremities one to stool *T*, the other to the head of case *C*, while the coils are loosely mounted upon a spindle fixed upon cross-bar *t* at its inner end by a small iron bracket, (shown in 80 Fig. 2,) while its outer end, extending through and projecting beyond leg *T*, forms pivot *e*. The bracket is not shown in Fig. 1, because it would conceal and be confounded with the coil of the spring. 85

The braces *D*, Figs. 1 and 2, are terminally pivoted to the head of the bed-case and to the body or legs of the stool, so as to open with and arrest their extension from each other, and to make them self-operative in releasing 95 the stool each brace is provided near its folding joint with a rigid strut or cam *d*, Fig. 1, projecting downward, so as to strike the floor *K* and bend the brace whenever the bed is swung up to position *y*, as shown at *d y*, Fig. 100 3, thus releasing the stool to the reactive force of the springs.

In the upright position of the bed the head of the case rests posteriorly upon the floor, as

shown at *c*, Figs. 3 and 4, the case still requiring the front-leg support of the upright stool, and the foot-rollers *R* stand not directly beneath, but a little in advance of the pivotal connection *e*, as shown relatively at *R* and *e*, Fig. 3, and the continued reaction of the springs should be sufficient to require an initial tripping forward of the stool by the toe of the operator applied beneath its cross-bar *t* when proceeding to swing down the bed. The stool then readily yields to force applied at handle *o* and tilts and rolls forward or backward with and in obedience to the swing of the case, forming with the head of the case an expanding and self-contracting floor-base until the case is inclined half-way to a horizontal position, when expansion is arrested by the braces, and the bed, with the aid of its head weight, stands securely upon its expanded floor-base in readiness to swing either way from position *y*; but when swung below position *y* its head rises from the floor and at once the braces take full effect, making the stool a rigid head-leg support, upon the foot-rollers of which the bed as a rigid whole is sufficiently poised to be easily swung to and from its horizontal position.

Next, as to the mechanism for fully inclosing the bedding within the single case *C*, a rigid foot-board lever-frame (shown separately in Fig. 6) is formed of the foot-board *f*, its two standards *F F*, and the cross-bar *J*, all framed together of a width outside the standards to fit closely yet loosely between the side boards of case *C*, and at *m*, Fig. 1, the lever-frame is hinged to the interior bottom of the case upon a line crosswise the case, so as to swing upon the hinges as a fixed fulcrum from the open position shown in Figs. 1 and 2 to the closed position shown in Fig. 4, its top following the arc dotted therefrom in Fig. 1. The head-board lever-frame (separately shown in Fig. 7), is formed of the head-board *h* and its two standards *H H*, framed rigidly together, and it likewise fits between the side boards of the case and swings upon fulcrum-pivots *n*, fixed at opposite points to the said side boards at *n*, Fig. 1, from the open position there shown to the closed position shown in Fig. 4; but instead of a weight-bearing cross-bar like *J* the head-board lever-frame has a pair of short round lugs *a* fixed upon the inside of the standards *H H*, one upon each standard and upon a line parallel to but removed from that of the fulcrum-pivots *n*. The guide-frame *g G*, of which Fig. 8 is a separate enlarged view, and consisting of a strong cross-bar *g*, terminating in a pair of short parallel arms *G*, is pivoted to the interior of case *C* at the opposite points *b*, Fig. 1, whence it extends loosely between the standards *H H*, where it rests and slides upon the lug-pins *a*.

To permit the guide-frame to descend to the very bottom of the bed-case, its lower corners are recessed to receive and permit the sliding of the lug-pins within its own

thickness, as shown at *Ga*, Fig. 8. The movable interior bed-bottom *I*, Fig. 1, preferably consisting of flat wooden spring-bars (shown flatwise in Fig. 4) at its ends, rests directly upon the vibrating cross-bars *g* and *J*, and between the standards of the lever-frames, being kept in place by small parting-stops *j*, nailed to the side of bar *J*, and common wood-screws *i*, securing the bars loosely to the bar *g*, and is thus supported and carried up and down by the oscillation of the lever and guide frames. The soft mattress and bedclothing, (not represented in the drawings,) when placed upon the elevated bed-bottom *I*, Fig. 1, will be sufficiently raised above the sides of the bed-case for convenient access until the bed is closed by turning down flatwise the lever-frames, causing a depression of the cross-bar *g* of the top of cross-bar *J* and of the whole of spring-bars *I*, by which the superincumbent bedding is sunk wholly within case *C*, the increased depth of the case at the head affording extra space for the pillows. A cord provided with a convenient hook and eye and tightly strained between the tops of the lever-frames, as shown at *h* in Fig. 3, holds the lever-frames closed, and the inclosed bedding being somewhat compressed its elastic pressure keeps the spring-bars *I* in place while the bed is in the upright position.

The position of the concealed parts when the bed is closed, though not lettered, is distinctly shown by dotted lines in the vertical portion of Fig. 3.

I do not claim a loose interior bed-bottom consisting of spring-bars supported at the ends; nor do I broadly claim a folding and upright swinging bed, nor the application to such a bed of a supporting-spring or of a counterpoising-weight; nor do I broadly claim as original the combination, with a bed-case, of pivoted leg-supports, with or without jointed retaining-braces, or with pivoted and folding head or foot boards, in a folding bed.

I do not claim any novelty whatever in the foot-leg support hinged to the case, as described, nor in the handle placed thereon, nor in the cord-fastening for the closed head and foot boards in a folding bed.

What I claim as my invention, and desire to secure by Letters Patent, is—

1. In an upright swinging bed, a bed-case standing when upright with its bottom in front and its head resting posteriorly upon the floor, in combination with a two-legged stool provided with a pair of foot-rollers, and at its top horizontally pivoted to the bottom of said bed-case, so as to alternately stand upright with and be oppositely inclined and thrust forward feet foremost by said bed-case, and a spring connecting to the head of said case said stool and imparting thereto elastic resistance as a front-leg support to said bed-case, substantially as described.

2. In an upright swinging bed, a bed-case standing when upright with its bottom in front and its head resting posteriorly upon

- the floor, in combination with a two-legged stool provided with a pair of foot-rollers and pivoted at its top transversely to the bottom of said bed-case, so as to alternately stand up-right with and be oppositely inclined and rolled forward by said bed-case, and a spring connecting to said bed-case said stool and imparting thereto elastic resistance as a front-leg support to said bed-case, and a pivoted folding brace provided with a self-dislodging cam, and connecting to said bed-case said stool, and arresting, holding, and releasing the same as a rigid head-leg support to said bed-case, substantially as described.
- 5 3. In an upright swinging bed, a rigid bed-case having a weight fixed to its head and standing when upright with its bottom in front and its head resting posteriorly upon the floor, in combination with a two-legged stool provided with a pair of foot-rollers and pivoted at its top to the bottom of said bed-case, so as to permit said case to incline forward from an upright half-way to a horizontal position, but only by tilting and thrusting forward, feet foremost, the said stool, and a pivoted folding brace connecting the head of said case and said stool and opening with and arresting their extension from each other, all as a means for making the head, along with its weight, an effective counterpoise to the foot of said bed-case in the more inclined positions of the bed, substantially as described.
- 10 4. In a folding bed, the combination, with a bed-case and a movable bed-bottom therein, of an oscillating lever-frame serving as a folding foot-board for the bed, but pivoted to the interior bottom of said case and having a cross-bar extending beneath and supporting one end of said bed-bottom between its stand-
- ards as a means for raising and lowering said bed-bottom within said bed-case, substantially as described.
- 15 5. In a folding bed, the combination, with a bed-case and a movable bed-bottom therein, of an oscillating lever-frame serving as a folding head-board for the bed, but pivoted to the interior sides and at the bottom of said case, and having its standards provided at the sides of said bed-bottom with lug-pins projecting beneath it, and an oscillating guide-frame transversely pivoted to the interior of said case, so as to project across and rest upon said lug-pins, and having a cross-bar extending beneath and supporting one end of said bed-bottom, all as a means for raising and lowering said bed-bottom in said bed-case, substantially as described.
- 20 6. A folding and upright swinging bed consisting of the bed-case C, the movable interior bed-bottom I, the oscillating head-board and foot-board lever-frames *h* H and *f* F J, and guide-frame *g* G, the lever and guide frames pivoted to said case and imparting vertical motion to the bed-bottom therein, and the two-legged stool T *t*, provided with the foot-rollers R and pivoted to the bottom of said case, and the springs S, connecting said stool to said case and imparting elastic resistance thereto as a front-leg support for said case, and the folding braces D, each provided with a self-dislodging cam *d*, and connecting to said case, and arresting, holding, and releasing said stool as a rigid head-leg support for said bed, substantially as described and set forth.
- 25 7. A folding and upright swinging bed consisting of the bed-case C, the movable interior bed-bottom I, the oscillating head-board and foot-board lever-frames *h* H and *f* F J, and guide-frame *g* G, the lever and guide frames pivoted to said case and imparting vertical motion to the bed-bottom therein, and the two-legged stool T *t*, provided with the foot-rollers R and pivoted to the bottom of said case, and the springs S, connecting said stool to said case and imparting elastic resistance thereto as a front-leg support for said case, and the folding braces D, each provided with a self-dislodging cam *d*, and connecting to said case, and arresting, holding, and releasing said stool as a rigid head-leg support for said bed, substantially as described and set forth.
- 30 8. A folding and upright swinging bed consisting of the bed-case C, the movable interior bed-bottom I, the oscillating head-board and foot-board lever-frames *h* H and *f* F J, and guide-frame *g* G, the lever and guide frames pivoted to said case and imparting vertical motion to the bed-bottom therein, and the two-legged stool T *t*, provided with the foot-rollers R and pivoted to the bottom of said case, and the springs S, connecting said stool to said case and imparting elastic resistance thereto as a front-leg support for said case, and the folding braces D, each provided with a self-dislodging cam *d*, and connecting to said case, and arresting, holding, and releasing said stool as a rigid head-leg support for said bed, substantially as described and set forth.
- 35 9. A folding and upright swinging bed consisting of the bed-case C, the movable interior bed-bottom I, the oscillating head-board and foot-board lever-frames *h* H and *f* F J, and guide-frame *g* G, the lever and guide frames pivoted to said case and imparting vertical motion to the bed-bottom therein, and the two-legged stool T *t*, provided with the foot-rollers R and pivoted to the bottom of said case, and the springs S, connecting said stool to said case and imparting elastic resistance thereto as a front-leg support for said case, and the folding braces D, each provided with a self-dislodging cam *d*, and connecting to said case, and arresting, holding, and releasing said stool as a rigid head-leg support for said bed, substantially as described and set forth.
- 40 10. A folding and upright swinging bed consisting of the bed-case C, the movable interior bed-bottom I, the oscillating head-board and foot-board lever-frames *h* H and *f* F J, and guide-frame *g* G, the lever and guide frames pivoted to said case and imparting vertical motion to the bed-bottom therein, and the two-legged stool T *t*, provided with the foot-rollers R and pivoted to the bottom of said case, and the springs S, connecting said stool to said case and imparting elastic resistance thereto as a front-leg support for said case, and the folding braces D, each provided with a self-dislodging cam *d*, and connecting to said case, and arresting, holding, and releasing said stool as a rigid head-leg support for said bed, substantially as described and set forth.
